(57) **CLAIM**

The ornamental design for a combined remote control unit and display stand for toy vehicles, as shown and described.

DESCRIPTION

FIG. 1 is an upper, front perspective view of a first embodiment combined remote control unit and vehicle display stand for toy vehicles in accordance with our new design;

FIG. 2 is a top plan view thereof;

FIG. 3 is a right elevation view thereof;

FIG. 4 is a bottom plan view thereof;

FIG. 5 is a left elevation view thereof; and

FIG. 6 is a rear elevation view thereof;

FIG. 7 is a front elevation view thereof;

FIG. 8 is an upper, front perspective view of a second embodiment combined remote control unit and vehicle display stand for toy vehicles in accordance with our new design;

FIG. 9 is a top plan view thereof;

FIG. 10 is a right elevation view thereof;

FIG. 11 is a bottom plan view thereof;

FIG. 12 is a left elevation view thereof;

FIG. 13 is a rear elevation first top view thereof;

FIG. 14 is a front elevation view thereof;

FIG. 15 is an upper front perspective view of a third embodiment combined remote control unit and vehicle display stand for toy vehicles in accordance with our new design;

FIG. 16 is a top plan view thereof;

FIG. 17 is a right elevation view thereof;

FIG. 18 is a bottom plan view thereof;

FIG. 19 is a left elevation view thereof;

FIG. 20 is a rear elevation first top view thereof; and,

FIG. 21 is a front elevation view thereof.
